5 Claims. (Cl. 202—176)

ABSTRACT OF THE DISCLOSURE

Apparatus for producing hot water and distilled water including a hot water tank with a condensing coil and collection trough in the vapor space, a top outlet for delivering hot water for domestic use, and a distillate outlet from the trough. The coil and trough can be contained in a separate tank or can be supported by a plug closing a port in the tank wall through which the coil and trough extend. A pump can pump hot water upward into the vapor space and an impeller can circulate air from the vapor space to the coil and return.

The disclosure

This invention relates to the supply of water, especially for household uses and the like. More particularly, this invention relates to the supply of both distilled water and hot undistilled water in a water supply system. It is the general object of this invention to provide a new and useful system for supplying distilled water.

It is also an object of this invention to provide a device which can be installed in a hot water heater to supply distilled water in quantities sufficient for household use.

A further object of this invention is to modify a hot water heater to supply distilled water in addition to undistilled hot water.

Still another object is to provide a new and useful device which may be added to a hot water heater for use in combination therewith for production of a supply of distilled water.

Another object is to provide new and useful improvements in flow systems in the production of distilled or purified water in accordance with any of the foregoing objects.

Other objects and advantages will be apparent from the following descriptions and from the drawings in which:

FIGURE 1 is a vertical section through a water heater showing a form of water distillation device usable in accordance herewith;

FIGURE 2 is a fragmentary vertical section through another water heater showing another form of water distillation device usable in accordance herewith; and

FIGURE 3 is a fragmentary showing, partly in section, of a system including a water heater and still another form of device associated with the water heater in accordance herewith.

While this invention is susceptible of embodiment in many different forms, there is shown in the drawings and will herein be described in detail several embodiments of the invention, with the understanding that the present disclosure is to be considered as an exemplification of the principles of the invention and is not intended to limit the invention to the embodiments illustrated.

Turning first to the form of device illustrated in FIGURE 1, there is provided a system which may be installed in a conventional hot water heater for connecting the heater to produce distilled water during the otherwise normal operation of the hot water heater. The device is illustrated as installed in the upper portion of a hot water heater. It will be evident that the system of FIGURE 1 can readily be installed in existing water heaters

2

to enable production of distilled water from the water heater.

Accordingly, the device includes a fitting 11 which carries a trough 12. The bottom of trough 12, as illustrated in FIGURE 1, is sloped to the right toward an outlet port 13 for draining any liquid collecting within trough 12. Connected to outlet port 13 and in communication therewith is drainage or discharge line 14 for draining or discharging liquid from trough 12. Line 14 is controlled by suitable hand valve 15 so that liquid within trough 12 may be selectively withdrawn. Mounted through fitting 11 and carried thereby is a condensing coil 16 which extends above trough 12 so that trough 12 is in position to collect any condensate forming on the outer surface of coil 16 and dripping therefrom.

In order to install the device, a female threaded nut 19 is provided which may be positioned as shown impaling wall or tank 20 and welded, or otherwise secured in place. Fitting 11 includes male threads 21 on an outer cylindrical surface thereof for association with the female threads of nut 19. A hexagonal surface 22 is provided on fitting 11 for engagement of the fitting with a wrench. For installation, nut 19 is secured by welding at the bore in tank 20 and fitting 11 is then inserted, trough end first, through nut 19 and the bore in tank 20. Fitting 11, upon engagement of threads 21 with the female threads of nut 19, is threaded into nut 19 and tightened with a wrench applied to surface 22. Trough 12 should be beneath coil 16 and the rotational disposition of fitting 11 may be adjusted for such purposes. Suitable union compound, sealant or the like may be provided on threads 21, as desired.

Each end of condensing coil 16 terminates in a length of tubing 23 or 24. Tubing 23 and 24 is flexible, e.g. copper or the like, and is connected by suitable unions respectively to a cold water branch pipe 25 and a supply line 26 for tank 20. Branch pipe 25 is a branch from the cold water main.

A body of water 29 is maintained within tank 20, supplied from cold water pipe 25, through coil 16 and line 26. A conventional water heater cold water line control valve 30 is provided in line 26 to control the level of water in tank 20, e.g. responsive to water level detected by water level detection system 28. Suitable conventional overflow (not shown) from tank 20 may be provided, as desired.

Fitting 11 and trough 12 can be formed, for example, of a 2" or 2½" pipe length closed at both ends and having one wall at least partially removed for exposure of coil 16 to the space within tank 20 above the body of water 29. The portion of the pipe wall removed would correspond to the upper portion as viewed in FIGURE 1, so that the remaining pipe forms trough 12. Outlet port 13 can be bored in the pipe portion with discharge line 14 connected thereto by a suitable tap or the like.

Considering tank 20 more particularly, tank 20 comprises a water heating chamber. Above bottom wall 31 of tank 20 is an electric resistance heating element 33 mounted through the wall of tank 20 by a watertight, electrically insulating gland 32. Heating element 33 is submerged in the body of water 29 for heating the body of water 29 to increase the vaporization of water from body 29. The vapor rises to a vapor chamber 35 above body 29. Any suitable source of electric energy is used, illustrated as a 220 v. AC line.

A hot water discharge pipe is provided in the form of a dip tube as the origin of the hot water main 34. The hot water discharge pipe opens sufficiently below the top of tank 20 to trap air in the top of tank 20, thereby providing an air space or vapor chamber 35 in which to insert the condenser system. The space is retained during opera-

tion of the heater partly by release of air and other gases from the water during heating.

In operation, heater element 33 heats the body of water 29 and vapors rise within vapor chamber 35 and, upon contact with the coil 16, condense. The condensate collects in trough 12 for discharge via line 14 upon opening valve 15. A charcoal filter 36 may be provided in line 14 to filter traces of absorbable materials which may carry over into the condensate.

The system illustrated in FIGURE 2 is of a form which would include the condensing and condensate recovery portion as an integral part of a hot water heater, such as may be constructed and marketed by a manufacturer, compared with the fitting type condenser and condensate recovery system described with reference to FIGURE 1.

The hot water heater of FIGURE 2 is indicated generally by reference numeral 40 and includes an outer casing of two parts, an upper cap and a lower bottom joined at a flanged junction and spaced by a gasket 41 having a large central opening. The bottom of the heater is defined by a watertight bottom wall 42 spanning the heater bottom and capable of supporting a body of water within a tank portion of the heater in the form of tank 44.

Above wall 42 within the bottom portion of the tank 44 an electric resistance heating coil 33, as described with reference to FIGURE 1, is mounted through the tank wall by watertight electrically insulating gland 43. Tank 44 is defined generally between bottom wall 42 and gasket 41 and normally contains a body of water. Above gasket 41 is a condensing chamber 45 for condensing and recovering purified water from water vapor rising from the body of water in tank 44. Tank 44 is also provided with a dip tube or hot water discharge pipe which is the origin of hot water main 34.

A motor 47 is mounted on the top wall of heater 40 and a drive shaft 48 depends from motor 47 through the top casing wall. Shaft 48 is connected to and drives a hollow cylinder or shaft 50, which is rotatably supported. An atomizer 49, having radial impeller blades, is mounted on the shaft 50, the atomizer serving the dual purpose to atomize water conducted thereto by means hereinafter to be described, and also to agitate the air to increase its evaporative effect. The lower portion of the shaft 50 is provided with an inlet communicating with water in the tank 44 to permit flow of water into the interior of the hollow shaft 50. A plurality of openings or ports 51 are provided in the shaft 50 near the location of the atomizer 32, and water issuing from the ports 51 is drawn by and impinges on the blades of the atomizer 49. Inasmuch as rotation of the shaft 50 causes the same to act in the nature of a pump drawing water from the tank 44 for emergence from the ports 51, the pumping action thereof has been by arrows designated by reference character 52.

Surrounding shaft 50 at the level of ports 51 is an annular space 55 which receives a spray of water from ports 51 as shaft 50 rotates. Annular space 55 has an annular opening 56 thereabove for communication of space 55 with atomizer 49. As atomizer 49 rotates with shaft 50, the atomizer draws air from space 55 through opening 56, and as the air travels through annular space 55 it is moistened or substantially saturated by the vapors from the hot water being ejected through ports 51. Atomizer 49 forces the resulting moist air through a demister 57 which separates water droplets from the air and the air is thereafter directed radially outward into a condensing zone 58. The water droplets separated by demister 57 are returned to annular space 55 and/or tank 44 by gravity.

The moist air, leaving demister 57, travels downwardly through the condensing zone 58 and is contacted with a condensing coil 59 disposed within zone 58. Condensing coil 59 is supplied with cold water from cold water branch pipe 25 through valve 60 and the water circulates through coil 59 and is discharged therefrom through outlet pipe 61 to tank 44. Thus, the condensing coil is cooled by cold

water in the inlet line to tank 44. Valve 60 may be controlled in the same manner as valve 30 in FIGURE 1 to supply water needs to tank 44 as in normal water heater operation.

5 Within condensing zone 58, in the bottom thereof, there is provided a condensate collection trough 62 which collects condensate formed on coil 59 in zone 58. The condensate is withdrawn through line 14 and filter 36 to condensate storage tank 67. Storage tank 67 provides a supply of purified or distilled water which may be tapped as needed or desired through valve 15.

10 After circulation in contact with coil 59, the air in condensing zone 58 leaves zone 58 adjacent the bottom thereof through a plurality, or circular array, of slots 63 in casing 64, and the air, as shown by the arrows 65 for direction of flow, is recycled back to space 55 for contact with additional water spray from ports 51. Thus, a cyclic stream of air is provided. The cyclic stream is moistened with a hot water spray to increase its vapor content even 15 to saturation and the stream is then directed to a cooling area where the moisture is partially removed by contact with condensing surfaces, the condensate being recovered as distilled water product and the air stream continuing to cycle alternatively through the moistening and condensing zones.

15 Casing 64 is a sheet metal casing which defines annular space 55 and zone 58 and which supports the demister 57. Casing 64 is mounted to the top wall of hot water heater 40 by means of a flange and bolts indicated generally at 20 30 35 40 45 50 55 60 65 70 75 80 85 90 95 100 105 110 115 120 125 130 135 140 145 I claim:

1. Apparatus for producing distilled water and hot undistilled water comprising a water tank, a condensing chamber, heating means for heating water in said tank to a temperature below the boiling point thereof, outlet means for supplying heated water from said tank to a hot water system, cooling means in said condensing chamber, a drivable shaft rotatably mounted in said condensing chamber, flow path means for providing an intimate contact between air and water vapor from said tank, means mounted on said shaft for circulating air through said flow path means to said condensing chamber, pump means for supplying water from said tank to said flow path means to provide increased water vapor in said flow path means, said pump means being mounted on and driven by said drivable shaft, motor means for driving said drivable shaft whereby air is circulated by said circulating means to carry water vapor from said flow path means into said condensing chamber and into intimate contact with the cooling means therein to condense water from said air, and means for withdrawing from the condensing chamber water condensed therein.

2. Apparatus for producing distilled water and hot undistilled water comprising a heating chamber and a cooling chamber, heating means for heating water in said heating chamber to a temperature below the boiling point thereof, outlet means for supplying heated water from said water heating chamber to a hot water system, means providing an air flow path for directing air from the heating chamber to the cooling chamber and return, means for forcing air along said flow path, means for introducing water vapor into the air in said heating chamber, air circulated by said air forcing means serving to carry water vapor into the cooling chamber wherein a portion of said water is condensed, means for withdrawing condensed water from said cooling chamber and means for directing the air into the heating chamber.

3. The apparatus of claim 2 including means in said air flow path between said heating chamber and cooling chamber for separating water droplets from the stream of air and water vapor.

4. Apparatus for providing distilled and undistilled hot water comprising a tank, means for maintaining the tank

partially filled with a body of water to provide a vapor space above the level thereof, means for heating the water in the tank, partition means defining a condenser zone in said vapor space and having an inlet, a condensing coil in the condenser zone, distillate collecting means positioned below the coil, means for introducing cold water into said coil, pump means for delivering hot water from the body of water upward into said vapor space for forming water vapor for passage through said inlet and to said coil, means for withdrawing distillate from said distillate collecting means, and means for supplying heated water from said tank to a hot water system.

5. Apparatus for providing distilled and undistilled hot water comprising a hot water tank for containing a body of hot water, a vaporizing tank, means for delivering hot water from said hot water tank to said vaporizing tank, means for maintaining the vaporizing tank partially filled with water to provide a vapor space above the level thereof, means for heating the water in the hot water tank, a condensing coil in the vapor space, distillate collecting means positioned below the coil in said vaporizing tank, means for introducing cold water into said coil, and means for withdrawing distillate from said distillate collecting means, said vaporizing tank being mounted with said vapor space above the top of said hot water tank, said delivering means comprising an outlet conduit extending from said hot water tank upwardly to said vaporizing tank and including an outlet from said vaporizing tank for delivering hot water therefrom to a hot water supply system.
